RECORD BINDER

Paul O. Unger, Chicago, Ill., assignor to Wilson-Jones Company, Chicago, Ill., a Corporation of Massachusetts

Application March 19, 1931. Serial No. 523,733

4 Claims. (Cl. 129—8)

This invention relates to a record binder in combination with a sheet compressor which is adapted for initially receiving the record sheets and maintaining the same in compressed form. 5 The binder and compressor are so constructed that the compressor can be readily impaled upon the posts of the binder whenever it is desired to do so.

The invention comprises the novel structure 10 and combination of parts hereinafter described and more particularly pointed out and defined in the appended claims.

On the drawings: Figure 1 is a fragmentary enlarged interior plan view of a record binder 15 involving this invention.

Figure 2 is an enlarged fragmentary cross sectional view taken upon the line II—II of Figure 1.

Figure 3 is a view similar to Figure 2 illustrating the parts in different position.

Figure 4 is a view similar to Figure 2 illustrating the parts in a still different position.

Figure 5 is an enlarged sectional view taken upon the line V—V of Figure 3 with parts shown 25 in elevation and showing the pintle slide in its operative position.

Figure 6 is a view similar to Figure 5 illustrating the pintle slide in its inoperative position.

Figure 7 is a plan view of the sheet compressor 30 showing parts in section.

Figure 8 is a view similar to Figure 1 illustrating the sheet compressor incorporated in the binder.

As shown on the drawings: As illustrative of 35 this invention, there is shown a record binder comprising a back member 1 having hinge plates 2 hinged thereto. These hinge plates 2 are designed to swing upon their pivot hinges as shown in Figure 4. Each hinge plate 2 has a 40 second hinge plate 4 welded thereto and impaling posts 3 extend through one hinge plate 2 and its accompanying hinge plate 4. The cover members 5 are hinged to the lower margins of the hinged plates 4 whereby the covers may be 45 swung relatively to the hinge plates 2 while the latter may be swung relatively to the back member 1.

The hinge plate 2 opposite the one carrying the posts 3 has a casing 6 welded thereto which 50 is suitably apertured for receiving the ends of the impaling posts 3. Within the casing 6 there is a pintle slide 7 which is suitably apertured as indicated at 8 for receiving the ends of the impaling posts. It will be noted that the apertures 55 8 are elongated to allow the pintle slide to

move relatively to the posts. The pintle slide has rounded projections 9 extending from one end of the elongated slots 8 and these rounded projections are adapted for engaging cylindrical holes 10 which are drilled partially through the 60 ends of the posts 3. The far end of the casing 6 is closed and a coil spring 11 is positioned between the far end of the casing 6 and the end of the pintle slide 7 for normally urging such pintle slide into locking engagement with the 65 posts 3. The other end of the casing 6 is closed except for a slot 12 through which a finger piece 13 projects. The inner end of the finger piece 13 is pivotally connected to the pintle 70 slide 7. The manner of connecting the finger piece 13 with the pintle slide in the present instance consists in forming a cylindrical head upon the end thereof and fitting the same into a suitable socket in the pintle slide. The finger piece 13 is provided with a suitable notch 14 75 which is adapted for engaging the end wall of the casing 6 when the slide has been moved to its inoperative position as shown in Figure 6 so that it is possible to lock the slide in its inoperative position when it is desired to disconnect the parts 80 of the binder. When it is desired to lock the impaling posts 3, the finger piece will be lifted upwardly from the position shown in Figure 6 so that the spring 11 may project the slide forwardly.

In Figure 7 there is shown a compressor which is designed for initially receiving the printed records which may be in the form of loose sheets or photographs or any similar device. This compressor has a base strip 15 which is substantially as long as the binder and of a width substantially equal to that of the hinge plate 2. Impaling posts 16 are secured to the base member 15 and a removable top member 17 is secured to the top of the posts 16. This top member 17 may be secured to the posts in any convenient manner for ready removal. In the present instance it is shown as connected to the posts by screws 18. The base and top members 15 and 17 of the compressor are suitably apertured for 100 receiving the impaling posts 3 of the binder.

When the compressor has been filled with records and it is desired to incorporate the same in the binder, the posts 3 are unlatched from the casing 6 and swung into the position shown 105 in Figure 4 in which position the compressor may be readily impaled upon the posts 3. It will of course be understood that the record sheets are provided with suitable apertures for receiving the impaling posts 3 in addition to the 110

posts 16. When the compressor has been impaled upon the posts 3 the parts may be swung into their closed positions and the finger piece 13 released for allowing the spring 11 to project the slide 7 to its operative position.

When the binder has been supplied with the records through the instrumentality of the compressor and it is desired to permanently lock the same, the partially severed portion 19 of the casing 6 may be hammered down to engage a notch 20 in the slide bar for permanently locking such slide bar against movement. The partially cut portion 19 is adapted to register with the notch 20, when the pintle slide is in its operative position as shown in Figure 5.

From the foregoing it will be apparent that a novel form of record binder has been provided in combination with a compressor that may be used for daily receiving the record sheets and holding the same in compressed form and from wrinkling and which may be readily impaled upon the impaling posts of the binder and permanently locked in the record binder when it is desired to do so.

I am aware that many changes may be made and numerous details of construction may be varied through a wide range without departing from the principles of this invention, and I therefore do not purpose limiting the patent granted hereon otherwise than necessitated by the prior art.

I claim as my invention:

1. In a record binder, a back member, a hinge plate hinged to one margin of said back member, impaling posts carried by said hinge plate, a hinge plate pivoted to the other margin of said back member, a casing carried by said second hinge plate, said casing having apertures for receiving said impaling posts, a pintle slide in said casing, said pintle slide and impaling posts

having interengaging means whereby said posts may be locked to said casing, plates welded to said hinge plates and cover members hinged to said last mentioned plates.

2. In a record binder, a back member, hinge plates pivoted to the longitudinal margins of said back member, impaling posts secured to one hinge plate, a casing secured to the other hinge plate and having apertures for receiving the free ends of said impaling posts, a pintle slide in said casing, said pintle slide and impaling posts having interengaging means for locking said posts to said casing, and a movable finger piece upon said pintle slide adapted for interlocking with said casing when said pintle slide is in its inoperative position. 80

3. In a record binder having a back member, a hinge plate pivoted to each longitudinal margin of said back member, impaling posts secured to one hinge plate, a casing secured to the other hinge plate and having apertures for receiving the impaling posts, a pintle slide in said casing, said impaling posts and pintle slide having interengaging means for locking said impaling posts to said casing, yielding means for normally urging said pintle slide into its operative position and a movable finger piece upon said pintle slide adapted for interlocking with said casing when said slide is in its inoperative position. 95

4. The combination with a binder having a back member, a plate hinged to one longitudinal margin of the back member, posts carried by said plate, said plate being swingable to bring said posts into an upwardly inclined plane and a sheet compressor having parallel members connected by posts and provided with apertures and adapted to be positioned upon said first mentioned posts when the same are upwardly inclined. 100
